[57] **CLAIM**

The ornamental design for a storage case for solar powered hearing aids, as shown and described.

DESCRIPTION

FIG. 1 is a front perspective view of a storage case for solar powered hearing aids, showing my new design, in a closed position;

FIG. 2 is a side elevation view thereof;

FIG. 3 is an opposite side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a front perspective view in an open position;

FIG. 9 is a side elevational view in an open position thereof;

FIG. 10 is an opposite side elevational view in an open position thereof;

FIG. 11 is a front elevational view in an open position thereof;

FIG. 12 is a rear elevational view in an open position thereof;

FIG. 13 is a top plan view in an open position thereof; and,

FIG. 14 is a bottom plan view in an open position thereof.
